UNITED STATES PATENT OFFICE.

JACOB R. SAMPLE, OF SUMMIT, MISSISSIPPI.

MACHINE FOR BEATING AND POLISHING RICE.

SPECIFICATION forming part of Letters Patent No. 244,316, dated July 12, 1881.

Application filed February 21, 1881. (No model.)

To all whom it may concern:

Be it known that I, JACOB R. SAMPLE, of Summit, in the county of Pike and State of Mississippi, have invented a new and useful Improvement in Machines for Beating and Polishing Rice, of which the following is a specification.

Figure 1 is a side elevation of my improvement. Fig. 2 is a sectional elevation of the same. Fig. 3 is a portion of the section shown in Fig. 2, enlarged. Fig. 4 is a longitudinal sectional elevation of a part of the beater, taken through the line *x x*, Fig. 2. Fig. 5 is a longitudinal sectional elevation of the polisher, taken through the line *y y*, Fig. 1.

Similar letters of reference indicate corresponding parts.

The object of this invention is to facilitate the removal of the hulls of rice and the cleaning and polishing of the kernels.

A represents the base bars or sills of the machine, which are made of sufficient length to give a stable support to the operating parts of the machine.

To the centers of the base-bars *A* are attached the lower ends of the uprights *B*, which are strengthened in position by the inclined braces *C*. The lower ends of the braces *C* are secured to the end parts of the base-bars *A*, and the upper ends of the said braces are secured to the opposite sides of the upper ends of the uprights *B*. The uprights *B* are connected at their upper ends by a cross-bar, *D*, and a little below their centers by cross-bars *E*, attached to their opposite sides. The braces *C* are also connected by cross-bars *F*, attached to their outer sides a little above their centers.

The beating or hulling drum is formed by attaching staves *G* to the edges of two heads, *H*, and is strengthened by hoops or bands *I*, of iron or other suitable material.

To the inner sides of the heads *H* and staves *G* are attached triangular ribs *J*, and in the inner surfaces of the said staves *G*, between the side angles of the triangular ribs *J*, are formed half-round grooves *K*, to form spaces for the kernels to escape around the rounded edges of the triangular ribs *L* without being crushed.

The ribs *L* are attached to the outer surface of the cylinder *M*, which is made solid to give it sufficient weight to properly beat or hull the

rice. The ribs *L* are made higher and narrower than the ribs *J*, to leave space for the rice and to allow the said rice to pass between them and the said ribs *J*, so that the said ribs *L* will act upon the rice in the grooves *K* in the same manner that a pestle acts upon grain in a mortar.

The ribbed cylinder *L M* is made smaller than the interior of the ribbed drum *G H J*, and is placed loose within the said drum, so as to be revolved by the friction of the ribs *J* upon the ribs *L* as the said drum is revolved.

To the centers of the heads *H* are secured gudgeons *N*, which revolve in bearings in the uprights *B*. One of the gudgeons *N* projects, and to it is attached a crank, *O*, when the machine is operated by hand, and a pulley when the machine is operated by power.

In one side of the drum *G H J* is formed a slot, *P*, through which the rice is received and discharged, and which is closed by a strip or narrow stave, *Q*, secured in place by hasps, staples, and keys, or other suitable means. When the rice has been sufficiently beaten the strip or stave *Q* is removed, the drum *G H J* is turned slot downward, and the rice is allowed to flow out into a vessel, *R*, placed beneath the said drum. The rice is guided into the vessel *R* by the inclined aprons *S*, attached to the cross-bars *E F*. The rice is kept from flowing off the aprons *S* at their side edges by cleats *T*, attached to them. As the rice is falling from the drum *G H J* it is subjected to an air-blast from the fans *U*, by which the hulls or chaff are blown away.

The journals of the fans *U* revolve in bearings in the braces *C*, and to one of the said journals or to the fan-shaft is attached a pulley, *V*, around which passes a band, *W*. The band *W* also passes around a pulley, *X*, attached to or formed upon the drum *G H J*, so that the fans *U* can be driven from the said drum.

From the vessel *R* the rice is poured into the polishing-drum through a hole, *Y*, in one of the heads *Z* of the said drum, which hole is then closed by a bung or other suitable means. The heads *Z* are attached to a shaft, *a*, which revolves in open bearings *b*, attached to the braces *C*.

To one of the journals of the shaft *a* is at-

tached a crank, *c*, by means of which the polishing-drum is revolved by hand; or the crank *c* can be replaced by a pulley and the said polishing-drum revolved from the beating-drum

5 G H J.

To the heads *Z*, at a little distance from their edges, are attached the ends of four (more or less) light square bars, *d*, by the contact of which with the rice the said rice is cleaned

10 and polished.

To the edges of the heads *Z* is attached wire-gauze *e*, to allow the dust and fine chaff rubbed from the rice to escape, which wire-gauze is made of such a fineness of mesh that the ker-

15 nels of rice cannot pass through the said gauze.

Having thus fully described my invention, I claim as new and desire to secure by Letters Patent—

In a rice-beater, the combination, with a solid longitudinally-ribbed cylinder, *M*, of a surrounding longitudinally slotted and ribbed cylinder, the ribs of the inner cylinder being relatively longer and narrower than the grooves of the outer cylinder, and the latter being provided with suitable means for rotat- 20 25 ing it, for the purpose specified.

JACOB REED SAMPLE.
